CALENDAR HOLDER OR THE LIKE

Walter L. Jones, Paris, Ill., assignor to W. O. Colson
Company, Paris, Ill., a corporation of Delaware

Filed Oct. 28, 1959, Ser. No. 58,096

Term of patent 7 years

(Cl. D74—5)

Fig. 1 is a front elevational view of the desk calendar holder or the like showing my new design;

Fig. 2 is an end elevational view thereof taken from the right of Fig. 1;

Fig. 3 is a rear elevational view thereof;

Fig. 4 is a view taken generally in the direction of the line 4—4 in Fig. 2; and

Fig. 5 is a sectional view taken along the line 5—5 in Fig. 4.

The calendar shown in dotted lines on the drawing is for illustrative purposes only.

I claim:

The ornamental design for a desk calendar holder or the like, as shown and described.
